UNITED STATES PATENT OFFICE.

GEORGE B. PRICE, OF TOPLIFF, UTAH.

SPRING BOOT AND OILER.

1,304,366.

Specification of Letters Patent.

Patented May 20, 1919.

Application filed July 22, 1918. Serial No. 246,066.

To all whom it may concern:

Be it known that I, GEORGE B. PRICE, a citizen of the United States, residing at Topliff, in the county of Tooele and State 5 of Utah, have invented new and useful Improvements in Spring Boots and Oiler, of which the following is a specification.

This invention is an improved spring boot and oiler, the object of the invention being 10 to provide a boot for covering an automobile spring and protecting the leaves thereof from dust, water and mud and also for use in applying oil to and retaining the oil on and between the leaves of the spring and 15 preventing the oil or grease from becoming mixed with sand or earth and from gumming and cutting and otherwise injuring the spring leaves, the object of the invention being to provide an improved device of this 20 character which is extremely simple in construction, which can be cheaply manufactured and which can be readily applied to and removed from an automobile spring.

With the above and other objects in view, 25 the invention consists in the construction, combination and arrangement of devices hereinafter described and claimed.

In the accompanying drawings:

Figure 1 is an elevation of an automobile 30 spring provided with a boot and oiler constructed and arranged in accordance with my invention.

Fig. 2 is a transverse sectional view of the 35 boot and oiler as arranged on a spring, the spring being indicated in dotted lines.

Fig. 3 is a plan of the inner side of my boot and oiler, showing the same in open, extended position.

Fig. 4 is a similar view showing the exterior of the boot and oiler.

My improved boot and oiler may be made of leather, imitation leather, or any other suitable water-proof and flexible material or fabric and is of a size and shape adapting 45 the same to be arranged on and to cover an automobile leaf spring. The boot and oiler 1 is provided with a lining 2 of any suitable absorbent material, such for instance, heavy canton flannel or wool and the lining which 50 is stitched or otherwise secured to the inner side of the boot has a loose side flap 3 which projects beyond one side of the boot. The opposite side edges of the boot are provided

with eyelets and are employed to fasten the boot on the side of the spring and to fit the 55 boot tightly around the spring. The boot is also provided with a flap 5 which is preferably made of the same kind of material as the boot and which is stitched to the boot at one side, and along the center of the boot as 60 at 6. This flap is provided at its outer edge with snap sockets 7 and the boot is provided at the opposite edge with snap studs 8 which are adapted to engage in the snap sockets so that the boot and flap may be secured together 65 on the under side of the spring, the boot and its flap completely covering the spring and the lining of the boot, the extended edge 3 of the boot lining covering and underlapping the lacing, as shown in 70 Fig. 2 and as will be understood. Hence, the boot serves to completely incase the spring, to tightly fit thereon, and to effectually prevent dust, dirt, mud, or water from getting between the leaves of the spring. 75

In order to enable the spring to be supplied with lubricating oil, for the protection of the leaves and to secure the desired action of the spring I provide the boot near its outer end with a nipple 9 through which 80 cylinder oil or other suitable lubricant may be supplied to the spring from an oil can and by inserting the nozzle of the can in the said nipple. To cover the nipple I provide a flap 10 at the outer end of the boot which 85 flap is preferably made of the same kind of material as the boot and as the flap 5 and can be opened independently of the flap 5 to uncover the nipple. The said outer flap, when closed, is secured by fasteners such as 90 95 the fasteners 7, 8 hereinbefore described.

My improved boot and oiler may be readily applied to or removed from the spring of an automobile or other vehicle and serves to effectually protect the spring from the 95 weather and from dust and mud, enables the spring to be readily oiled and the lining of the boot which absorbs the lubricant oil also serves to supply the oil to the spring as required so that the boot need only be supplied 100 with oil at considerable intervals in order to keep the spring in good condition and thoroughly lubricated.

Having thus described my invention, I claim:

105 A spring boot made of flexible material

and adapted to be fitted around a leaf spring, said boot having lacing openings at opposite sides and being provided with a lining one side of which projects beyond one side of the boot and to underlap and cover the lacing, the boot being also provided on its outer side with a flap which is secured to the center of the boot longitudinally and projects

beyond the same side of the boot as the extension of the lining, said flap being provided at its outer side and the said boot being provided at the opposite side with fasteners to enable said flap and boot to be secured together and around the spring. ¹⁰

In testimony whereof I affix my signature. ¹⁵
GEORGE B. PRICE.
